United States Patent Office

Des. 208,090
Patented July 18, 1967

208,090

MULTI-STORIED BUILDING

George D. Tesch, 922 N. Dilley Road,
Gurnee, Ill. 60031

Filed June 2, 1966, Ser. No. 2,523

Term of patent 14 years

(Cl. D13—1)

Fig. 1

Fig-2

Fig-3

FIGURE 1 is a top plan view, showing my new design;
FIGURE 2 is an elevational view thereof;
FIGURE 3 is a sectional view taken substantially on the section line 3—3 of FIGURE 2, looking in the direction of the arrows; and

FIGURE 4 is a further sectional view, taken on the line 4—4 of FIGURE 1, looking in the direction of the arrows.

I claim:

The ornamental design for a multi-storied building, substantially as shown.
